(Cl. D13—1)

FIG. 1.

FIG. 2.

FIG. 3.

Figure 1 is a perspective view showing the front and right-hand side of a commercial building embodying my new design.

Figure 2 is a perspective view showing the front and left-hand side of the building shown in Figure 1.

Figure 3 is a side elevation taken from the right hand side of the building shown in Figure 1.

The rear wall of the building and roof are both substantially plain.

The essential features of my design reside in the portions shown in full lines.

I claim:

The ornamental design for a commercial building, as shown and described.
